[57] CLAIM

I claim the ornamental design for the lighted sport design on an athletic shoe, as shown and described.

DESCRIPTION

FIG. 1 is a top plan view of the new ornamental lighted sport design on an athletic shoe of the present invention.

FIG. 2 is a front view thereof.

FIG. 3 is a right side view thereof.

FIG. 4 is a rear view thereof; and,

FIG. 5 is a bottom plan view thereof.

The broken line showing of the shoe in the FIGURES is for illustrative purposes only and forms no part of the claimed design. The broken lines which surround and extend from the soccer player and mid-sized ball designs indicate stitching and form no part of the claimed design.
